HELMHOLTZ RESONATOR DETONATION ATTENUATION MEANS FOR INTERNAL COMBUSTION ENGINES

Albert G. Bodine, Jr., Van Nuys, Calif.

Original application July 2, 1951, Serial No. 234,688, now Patent No. 2,573,536, dated October 30, 1951. Divided and application October 24, 1951, Serial No. 252,818, now Patent No. 2,738,781, dated March 20, 1956. Divided and application December 6, 1955, Serial No. 551,263. Again divided and this application April 16, 1956, Serial No. 578,475

1 Claim. (Cl. 123—191)

This invention relates generally to internal combustion engines and to means for suppressing irregular burning and detonation of fuel-air mixture therein. The invention is based on my discovery that detonation in combustion engines involves acoustic phenomena and can be alleviated by means of certain acoustic apparatus used in combination with the combustion chamber.

The present application is a division of my copending application Serial No. 551,263, filed December 6, 1955, allowed February 15, 1956, entitled Piston Carried Detonation Suppression Means for Internal Combustion Engines. That parent application was in turn a division of my application Serial No. 252,818, filed October 24, 1951, entitled Engine Detonation Control by Acoustic Methods and Apparatus, now Patent No. 2,738,781, which application was a division of my earlier application Serial No. 234,688, filed July 2, 1951, entitled Engine Detonation Control by Acoustic Methods and Apparatus, now Patent No. 2,573,536.

The present invention is based on the fact that detonation in an engine combustion chamber produces sound waves, a large part of which rise to high amplitude at resonant frequencies of the chamber, and on my discovery that the sound waves produce the various well-known and harmful manifestations of detonation. According to my basic invention, I inhibit or attenuate these harmful effects by interfering with or attenuating the high amplitude detonation-induced sound waves, and this is done by use in connection with the combustion chamber of acoustic attenuation means made responsive to the frequencies at which the detonation induced sound waves build up to high amplitudes.

The object of the present invention is the provision of an especially simple and effective acoustic attenuator means for the combustion chamber of an internal combustion engine, adapted for piston mounting, having the

2

advantage of ease of incorporation in the piston, and low cost.

The invention will best be understood from the following detailed description of an illustrative embodiment thereof, reference for this purpose being had to the accompanying drawing showing a vertical transverse section through an internal combustion engine, the section passing medially through the piston and piston mounted attenuators.

With reference to the drawing there is shown an illustrative L-head engine comprised of water-cooled block 10, water-cooled head 11, piston 12 working in cylinder 13 in head 10, exhaust valve 16, and spark plug 17.

An intake valve, not shown, will be understood to be located alongside exhaust valve 16, out of the plane of the drawing. Head 11 has an inner combustion chamber wall 20, enclosing a combustion chamber space 21 over the cylinder and valves, as shown. A plurality of Helmholtz resonators 24 are incorporated in the head wall of the piston. Each resonator is formed by a bore 25 extending upwardly through the head wall of the piston merely to the top surface thereof, and by a smaller bore 26 extending from bore 25 through the top surface of the piston, the latter forming the neck of the resonator. The bottom of bore 25 is then closed by a plug 27, which may be secured in place by peening, as indicated at 28. Helmholtz resonators whose necks communicate with the combustion chamber are thus formed in the head wall of the piston by a very simple and inexpensive operation, lending itself readily to incorporation in conventional piston structures.

The attenuation of detonation in internal combustion engines by use of Helmholtz resonators tuned to be resonant to detonation frequencies has been fully explained in my aforementioned Patent No. 2,573,536, and need not be repeated herein.

It will be understood that the drawings and description are merely illustrative of one specific embodiment of the invention, and that various changes in design, structure and arrangement may be made without departing from the spirit and scope of the appended claim.

I claim:

For use with an internal combustion engine having a combustion chamber and a cylinder opening into said chamber, a piston adapted for reciprocation in said cylinder, said piston having a top wall, and a Helmholtz cavity in said top wall formed by a bore extending upwardly into said piston wall from the lower side thereof, a smaller bore extending from said first mentioned bore through the top side of said wall, and a plug closing the lower end of the first mentioned bore.
